(57) **CLAIM**

The ornamental design for a bag collection assembly, as shown and described.

DESCRIPTION

FIG. 1 is a front, top and left side perspective view of a bag collection assembly according to the invention;

FIG. 2 is a front view thereof;

FIG. 3 is a left side perspective view thereof;

FIG. 4 is a rear view thereof;

FIG. 5 is a right side perspective view thereof;

FIG. 6 is a top view thereof;

FIG. 7 is a bottom view thereof;

FIG. 8 is a rear, bottom, left side perspective view thereof; and,

FIG. 9 is a front, top, left side perspective view thereof, showing the bag collection assembly in a position of use with a cap removed for ease of illustration.

1 Claim, 6 Drawing Sheets
